(57) **CLAIM**

The ornamental design for a combined speaker box and an amplifier, as shown and described.

DESCRIPTION

FIG. 1 is a front, top, right perspective view of a combined speaker box and an amplifier showing our new design;

FIG. 2 is an enlarged rear, top, right perspective view thereof; FIG. 3 is a rear elevational view thereof;

FIG. 4 is a right side elevational view thereof;

FIG. 5 is a top plan view thereof; and

FIG. 6 is a bottom plan view thereof.

FIG. 7 is an enlarged front, top, right perspective view thereof along the lines 7-7 and 7'-7' of FIG. 1;

FIG. 8 is an enlarged rear elevational view thereof along the lines 8-8 and 8'-8' of FIG. 3; and,

FIG. 9 is an enlarged right side elevational view thereof.

Portions in broken lines are for illustrative purpose only and form no part of the claimed design.
